Primary Examiner — Dominic V Simone*(74) Attorney, Agent, or Firm* — Leydig, Voit & Mayer, Ltd.(57) **CLAIM**

The ornamental design for a sandal, as shown and described.

DESCRIPTION

FIG. 1 is a top right front perspective view of a first embodiment of the sandal showing my new design;

FIG. 2 is a left rear perspective view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof;

FIG. 8 is a bottom plan view thereof; and

FIG. 9 is a top plan view thereof, having the laces hanging loosely;

FIG. 10 is a top right front perspective view of a second embodiment of the sandal showing my new design, having the laces unclaimed;

FIG. 11 is a left rear perspective view thereof;

FIG. 12 is a left side elevational view thereof;

FIG. 13 is a right side elevational view thereof;

FIG. 14 is a front elevational view thereof;

FIG. 15 is a rear elevational view thereof;

FIG. 16 is a top plan view thereof;

FIG. 17 is a bottom plan view thereof; and,

FIG. 18 is a top plan view thereof, having the unclaimed laces hanging loosely.

Any broken lines in the drawings indicate portions which form no part of the claimed design.
